US00D976935S

(12) **United States Design Patent** (10) Patent No.: **US D976,935 S**
(45) Date of Patent: **** Jan. 31, 2023**

(54) **DISPLAY PANEL WITH A GRAPHICAL USER INTERFACE**

(71) Applicant: **LG ELECTRONICS INC.**, Seoul (KR)

(72) Inventors: **Hyein Jung**, Seoul (KR); **Yongdeok Lee**, Seoul (KR); **Hyeran Jang**, Seoul (KR); **Hwajun Oh**, Seoul (KR)

(73) Assignee: **LG ELECTRONICS INC.**, Seoul (KR)

(**) Term: **15 Years**

(21) Appl. No.: **35/512,990**

(22) Filed: **May 24, 2021**

(80) **Hague Agreement Data**

Int. Filing Date: **May 24, 2021**

Int. Reg. No.: **DM/214511**

Int. Reg. Date: **May 24, 2021**

Int. Reg. Pub. Date: **Nov. 26, 2021**

(30) **Foreign Application Priority Data**

Dec. 8, 2020 (KR) 30-2020-0060498
